Inventor:

LeRoy D. Keehn,

by Robert Burns,
Atty

UNITED STATES PATENT OFFICE.

LE ROY D. KEEHN, OF CHICAGO, ILLINOIS.

SHOE-SOLE PROTECTOR.

Application filed May 31, 1924. Serial No. 716,960.

To all whom it may concern:

Be it known that I, LE ROY D. KEEHN, a citizen of the United States of America, and a resident of Chicago, in the county of Cook and State of Illinois, have invented a certain new and useful Improvement in Shoe-Sole Protectors, of which the following is a specification.

This invention relates to that type of protectors for shoe soles in which metallic wear plugs or the like are embedded in the material of the shoe sole, and exposed at the surface of said sole to afford wear resisting properties thereto. And the present improvement has for its object:

To provide a structural formation and arrangement of parts and features whereby metallic wear studs or brads of a headed form are inserted obliquely into the shoe sole and from the exposed edge thereof, to protect said edge, and with the gradual wear of parts in use, provide a gradual exposure of the lowermost portions of the studs or brads commensurate with such wear of the shoe sole, all as will hereinafter more fully appear.

In the accompanying drawings:

Fig. 1 is an under perspective view of a shoe having the present improvement applied.

Fig. 2, is a bottom view of the front part of a shoe sole with a similar application.

Figs. 3, 4 and 5, are companion detail vertical sections, illustrating the progressive steps in the application of the invention to a shoe sole.

Figs. 6 and 7, are side elevations of the headed brad used in carrying out the invention.

Like reference numerals indicate like parts in the several views.

As represented in the drawing, the wear resisting elements of the present invention consist of headed brads, each having a main shank portion 1, one end of which is tapered to a point, with said point split longitudinally to provide clinching tangs 2 in the final driving operation of the brad into position. The other end of the shank 1 is

formed with a head 3, the outer surface of which is of a crown or convex form, while its inner surface is of a cone form merging into the end of the shank 1 as shown.

In carrying out the present invention a plurality of holes 4 are bored in the outer sole and partly into the middle or inner sole of the shoe in an oblique direction from the front and lower exposed edge of said outer sole, as shown more particularly in Fig. 3. A stud or brad of the before described formation is driven into a hole 5, and in reaching the partially formed extension of said hole in the middle or inner sole of the shoe, the points of each brad separates laterally to cause a clinching of the brad in place. In such driving of the stud or brad into place the material of the outer sole adjacent to the headed portion of the stud or brad is displaced downwardly from the tread surface of the outer sole, as illustrated in Fig. 4, and the final operation then consists in grinding away such downwardly projecting part of the outer sole and any depending portion of the stud head, to a plane even with the tread surface of the sole.

The invention is more particularly designed for use on the toe portion of the shoe sole, the scope of the invention however embraces an application in manner above described to a side edge of the shoe sole as illustrated in Figs. 1 and 2.

Having thus fully described my invention what I claim as new and desire to secure by Letters Patent is:—

A shoe having a sole provided with an obliquely inclined opening extending from the lower edge of the sole, in combination with a wear resisting means comprising a stud fitting said opening and having a coniform head at one end of its shank and a split point at the other end adapted to spread apart in a final driving operation on the stud.

Signed at Chicago, Illinois, this 28th day of May, 1924.

LE ROY D. KEEHN.
